ELECTROCAPILLARY CONTRIVANCE.

1,076,445.

Specification of Letters Patent. Patented Oct. 21, 1913.

Application filed October 6, 1911. Serial No. 653,194.

To all whom it may concern:

Be it known that I, AXEL ORLING, subject of the King of Sweden, residing at No. 222 Seely road, Tooting, London, England, have 5 invented new and useful Improvements in Electrocapillary Contrivances, of which the following is a specification.

This invention relates to improvements in electro-capillary contrivances having for 10 their object the augmentation of the rapidity, amplitude and force-action of the displacement along the convergent capillary passage of the mercury-electrolyte meeting surface which results from the passage of 15 an electric impulse through the contacting liquids.

According to the present invention the mercury is forced to occupy a portion of the convergent capillary passage which is of 20 smaller bore than that which it would occupy if left free, this force being derived by subjecting the smaller end of the convergent capillary passage to a pressure which is less than that of the atmosphere to 25 which the larger end is exposed. Under such circumstances a very small mass of mercury will be endowed with a relatively considerable amount of energy of recovery from the constrained position and be capable of responding with great rapidity and 30 precision to any change in the surface-tension of the mercury, resulting from the passage of an electric impulse, by undergoing displacement along the length of the capillary passage.

The invention includes means for adjusting the difference of pressure at the two ends of the capillary passage and for effecting the incidence of the displaced mercury on a 40 suspended oscillating member for the purpose of indicating and recording the passage of the electric impulses.

The accompanying drawing shows, as representative examples, forms of construction 45 which embody the above described invention in a very simple and efficient manner.

In this drawing: Figure 1 is an isometric elevation of an instrument, embodying the above described invention, adapted to indicate and record a rapid succession of mixed positive and negative impulses. Fig. 2 shows, on an enlarged scale, one form of construction of the new electro-capillary element which constitutes the fundamental 55 feature of this invention. Fig. 3 shows a

modified construction whereby the position of the mercury within the converging capillary passage can be adjusted, Fig. 4 being a section taken along the line 4—4 of Fig. 3. Fig. 5 shows a form of construction which 60 is alternative to that shown in Figs. 3 and 4.

Referring first to Fig. 2, *a a* are two like convergent capillary tubes the bore of which, at the smaller end, is about $\frac{1}{10}$ to $\frac{1}{8}$ of an inch in diameter. Into the larger ends of 65 these tubes some mercury is inserted and, by means of plugs not shown in the drawing which are temporarily inserted in the larger ends, the mercury is forced toward the smaller ends of the capillary tubes. The 70 unoccupied portion of the smaller ends of the tubes are then filled with an electrolyte such as weak sulfuric acid for example. A U-shaped tube *b* is then filled with the like electrolyte and the smaller ends of the 75 tubes *a a* are inserted in the open ends thereof and sealed therein in a manner to exclude the admission of air. The above mentioned plugs are subsequently removed, whereupon the mercury will tend to retreat from the 80 smaller portions of the capillary tubes but will be prevented from so doing by the fact that the consequence of an actual retreat would be the production of a vacuum within the U-shaped tube *b*, since the electrolyte is 85 non-expansible. Under such circumstances the mercury will be constrained to continue to occupy the smaller ends of the capillary tubes by the excess of pressure of the atmosphere, acting at the larger end, over the pressure 90 within the interior of the U-shaped tube *b*, which pressure will automatically become less than that of the atmosphere to a degree which is just sufficient to balance the surface-tension effort of the mercury to move 95 toward the larger end of the capillary tube. If now an electric impulse be transmitted through the electrolyte from the mercury in one tube to that in the other, the surface tension of the mercury at the inner end of that 100 at which the impulse enters will be momentarily relaxed, whereas the surface tension at the inner end of the mercury in the other tube will be increased. There will in consequence be an immediate displacement of 105 the mercury in the direction of the passage of the electric impulse and a very rapid recovery to the normal position on the cessation of the impulse.

The rate at which the mercurial displace- 110

ment will respond to the making and breaking of the electric circuit is very much greater than that which will occur when the mercury is forced into the constriction 5 under the action merely of a small amount of gravitational force such as has hitherto been employed. One reason for the increased rapidity is due to the fact that the mass to be moved is very much less, and another reason is the greater intensity of the force action which is rendered available for effecting displacement when the surface tension of the mercury, which is in a state of exaggerated strain, undergoes a change by 10 the passage of an electric impulse.

To facilitate the direct incidence of the mercury on a freely suspended indicator or recorder, the unoccupied portions of the capillary tubes are filled with mercury sufficiently to allow the globular extremities thereof to protrude beyond the ends of the capillary tubes and, to minimize the quantity of such added mercury, the portions of the tube which carried the plugs, temporarily 20 employed, may be cut off.

An alternative construction whereby the mercury can be forced to occupy the smaller portions of the convergent capillary tubes *a a* is shown in Figs. 3 and 4 in which the 30 U-shaped tube *b* is provided with a branch *b*¹ which is closed by an elastic chamber *b*² the volume of which is adapted to be adjusted by a screw *b*³. The wall of this chamber may, for example, be composed of thick rubber. The tubes *a a* are inserted and sealed into the U-shaped tube *b* when the chamber *b*² is in the contracted condition and, subsequently on unscrewing the screw *b*³ the expansion of the chamber *b*² will cause the 40 mercury to be drawn toward the smaller ends of the capillary tubes to any adjusted degree that may be desirable.

In Fig. 5 which shows a construction alternative to that shown in Figs. 3 and 4, the tube *b* which contains the electrolyte is capable of being regulated in respect to its volume capacity by closing the end, remote from the capillary tubes *a a*, by a rubber cap *b*⁴, the diaphragm portion of 50 which can be adjusted in position by means of a screw *b*⁵.

Referring to Fig. 1, *c* is a frame on which is mounted the new electro-capillary element *a—b* and, in contact with the protruding mercury thereof, a plate *d* composed of an electrical insulating substance, such as mica for example, is so mounted as to be capable of being freely vibrated about a vertical axis by wires *d*¹ *d*². The disk is provided, on one border thereof, with an electrically conducting surface *e*¹, connected to the wire *d*¹, against which abuts the protruding mercury of one of the tubes *a* and insulated therefrom, on the opposite border of 60 the plate another conducting surface *e*², con-

nected to *d*², against which abuts the protruding mercury of the other tube *a*. In such a manner an electric circuit through the conducting wires *d*¹ *d*² will be completed through the mercury and electrolyte contained in the electro-capillary element *a—b*, and by the passage of an electric impulse, the plate *d* will be angularly displaced by the consequent further protrusion of the mercury from one of the tubes *a* and the corresponding retirement of the mercury within the other tube *a*. By means of a screw *f* the pressure of the mercury on the contacting surfaces *e*¹ *e*² can be adjusted. Secured to the plate *d* is a siphon recorder *g* one end *g*¹ of which dips into a chamber *h* of ink while the other end *g*² rests lightly on a strip of paper *k* which, in the usual manner is caused to progress uniformly and carry the record of the electric impulses marked thereon as the result of the angular displacements of the plate *d*. To eliminate friction between the paper *k* and the extremity *g*² of the siphon recorder, a trembler is provided in the usual way as for example by an induced intermittent electric current in a helical wire *n*. To permit the sequence of electric impulses to be viewed on a considerable scale of amplitude, a small reflecting mirror *n* may be carried on the axis of suspension 95 of the plate whereby a telegraphic message may be read by a person conversant with the code of transmission.

I claim:

1. An electro-capillary contrivance comprising two converging capillary tubes occupied by mercury, a closed chamber containing an electrolyte into which the smaller ends of the capillary tubes are sealed and within which a pressure less than that of the atmosphere is maintained and means for transmitting electric impulses from the mercury in one tube to that in the other through the interposed electrolyte.

2. An electro-capillary contrivance comprising two converging capillary tubes occupied by mercury, a closed chamber containing an electrolyte into which the smaller ends of the capillary tubes are sealed and within which a pressure adjusted to a suitable degree less than that of the atmosphere is maintained and means for transmitting electric impulses from the mercury in one tube to that in the other through the interposed electrolyte.

3. An electro-capillary contrivance comprising two converging capillary tubes occupied by mercury, a closed chamber containing an electrolyte into which the smaller ends of the capillary tubes are sealed and within which a pressure less than that of the atmosphere is maintained and a pivoted plate whose surface makes contact with the exposed surfaces of the mercury contained in the capillary tubes and forms a portion 130

- of an electric circuit which conveys electric impulses from the mercury in one tube to that in the other through the interposed electrolyte.
- 5 4. An electro-capillary contrivance comprising two converging capillary tubes occupied by mercury, a closed chamber containing an electrolyte into which the smaller ends of the capillary tubes are sealed and 10 within which a pressure less than that of the atmosphere is maintained, a pivoted plate whose surface makes contact with the exposed surfaces of the mercury contained in the capillary tubes and forms a portion of an electric circuit which conveys electric 15 impulses from the mercury in one tube to that in the other through the interposed electrolyte, and means for recording the angular displacements of the said pivoted plate.
- In testimony whereof I have signed my 20 name to this specification in the presence of two subscribing witnesses.
